John E. Chambers, Shelbyville, Ind.

Application October 11, 1937, Serial No. 168,323

18 Claims. (Cl. 126—39)

In gas ranges employing a thermostatic control of oven temperature it is customary to provide a pilot burner and a main burner and to regulate the supply of gas to the latter by means of a temperature-responsive valve. One difficulty encountered in such an arrangement arises from the fact that the temperature-responsive valve, because of slow opening or slow or imperfect closing, will under some conditions pass gas at a rate insufficient to maintain combustion at the ports of the main burner. To overcome this difficulty, it has been proposed to install around the temperature-responsive valve a by-pass which will provide gas-flow at the minimum rate required to insure maintenance of combustion, and to employ the temperature-responsive valve only to vary gas supply over a range above this minimum rate.

The by-pass arrangement just described is open to the objection that in order to insure against 20 extinguishment of the flame in a main burner having sufficient capacity to raise the oven to the maximum desired temperature within a satisfactorily short time, the minimum rate of gas flow provided by the by-pass is too high to be economical and, especially in the case of an insulated oven, too high in some instances to prevent oven temperature from rising unduly above the value at which it is desired to maintain it.

It is the purpose of my invention to overcome the difficulties above noted and to provide a gas burner which will operate at maximum efficiency when supplied with its full quota of gas but which will produce a stable flame at minimum rates of gas-flow considerably lower than any possible with safety in prior arrangements. A further object of my invention is to provide an arrangement in which gas leaking past a nearly closed temperature-responsive valve in quantity insufficient of itself to maintain combustion will nevertheless be burned and prevented from escaping. Still another object of my invention is to eliminate the necessity for a pilot burner as a separate element in association with a thermostatically controlled main burner.

In carrying out my invention, I form the burner with two independent passages for the combustible mixture of gas and air, and I provide each of such passages with a series of discharge orifices. The supply of gas to one of these passages is controlled by an automatic valve responsive to oven temperature, while the supply of gas to the other passage is fixed at the minimum rate necessary to maintain combustion at the orifices of that passage. The main gas passage, 55

or that associated with the automatic valve, has each of its discharge orifices arranged in igniting relationship to an orifice of the other passage, so that any gas escaping from the main-passage orifices in quantity insufficient to maintain combustion will burn with the gas emerging from the orifices of the other passage.

The accompanying drawings illustrate my invention: Fig. 1 is a horizontal section through the oven of a gas range, showing my improved burner in place therein; Fig. 2 is a fragmental vertical section on the line 2—2 of Fig. 1; Fig. 3 is a vertical section on an enlarged scale on the section line 3—3 of Fig. 1; Fig. 4 is a plan view of a modified form of burner; Fig. 5 is a vertical section on the line 5—5 of Fig. 4; Fig. 6 is a vertical section on the line 6—6 of Fig. 4; and Fig. 7 is a section on the line 7—7 of Fig. 5.

The oven 10 illustrated in the drawings has insulated walls 11 and a suitable door 12. The burner, which is disposed in the oven a short distance above the floor thereof, is hollow and, in the arrangement shown in Figs. 1 to 3, substantially U-shaped in plan. The interior of the burner is divided into two passages 14 and 15 by a partition 16 which extends from one end of the burner to the other in spaced relation to the side walls thereof. Communicating with the passage 14, conveniently at the middle of the intermediate leg of the U-shaped burner, is a main mixture-supply conduit 17 formed near its inlet end with a venturi 18 and provided with a conventional mixing valve 19 for the admission of primary air. A similar conduit 17', having a venturi 18' and mixing valve 19', communicates with the gas passage 15 of the burner. The burner is provided with a series of discharge orifices 22 for the passage 14 and with a second set of discharge orifices 23 for the passage 15. Each orifice 15 is disposed adjacent an orifice 14, and each such pair of adjacent orifices is desirably located at or near the bottom of a recess or port 21 provided in the burner above the partition 16.

Gas for the two mixture conduits 17 and 17' is supplied from a main gas line 25 and through two branches 26 and 27 to the mixing valves 19 and 19', respectively. In the branch 26, I provide an adjustable temperature-responsive valve 28 controlled by a temperature-responsive element 29 associated with the oven 10, and in the branch 27 I provide a manually controlled valve 30 adapted for adjustment to a fixed position controlling the minimum supply of gas to the

burner. A main gas valve 31 located in the main supply line 25 is employed to shut off the supply of gas to both branches 26 and 27.

In operation, the valve 31 is opened and the burner ignited, preferably at one or more ignition ports 33 provided in the burner at the point where the conduit 17' joins the passage 15. If the oven is cold at this time, the temperature-responsive valve 28 will be open, and gas will be supplied through the conduits 17 and 17' to both passages 14 and 15. Gas from both such passages will pass through the openings 22 and 23 into the ports 21 and will emerge from each port, in effect, as a single stream. As the temperature of the oven approaches that for which the valve 28 is set, the temperature-responsive element 29 will operate to control the valve 28 in such a way as to maintain the desired oven temperature. As the valve 28 moves toward closed position under regulation by the temperature-responsive element 29, the amount of gas supplied to the passage 14 will be decreased and will eventually reach a point at which it would be insufficient of itself to maintain combustion; but because all combustible material passed by the valve 28 emerges from the orifices 22 in proximity to the burning gas from the orifices 23, any small quantities of gas leaking past the valve 28 when nearly closed will be consumed. If the temperature-responsive element 29 completely closes the valve 28, the only gas received by the burner will be that supplied through the conduit 17' to the passage 16. The valve 30 is so adjusted that this amount of gas will burn with a very low flame which will cling to the walls of the port 21 and will be stable.

It is to be noted that the path traversed by the gas supplied through the valve 30, conduit 17', passage 15, and openings 23 is entirely independent of the path over which flows the gas controlled by the temperature-responsive element 29. Because of this, the diameters of the openings 23, the cross-sectional area of the conduit 17', the shape of the venturi 18', and the mixing valve 19' can be such as to provide for the most efficient burning of the minimum supply of gas and for a gas velocity sufficient to prevent back-firing, while the openings 22, conduit 17, venturi 18, and mixing valve 19 can be designed for most efficient operation of the main gas supply.

In the modification of my invention illustrated in Figs. 4 to 7 inclusive the burner is of an elongated shape and is intended to extend transversely across the oven 10 preferably near the front end thereof. The burner comprises two elongated portions 40 and 41, the former having a longitudinally extending central opening in which the latter is received. If desired, the two portions 40 and 41 may be formed as parts of a single casting, being joined together by bridge-like members 42. The portion 40 is hollow to provide a mixture-passage 43 communicating with a mixture-supply conduit 44 which joins the portion 40 conveniently near its center. The portion 41 is likewise hollow to provide a passage 45 communicating with a mixture-supply conduit 46.

The side walls of the burner-portion 41, as is clear from Fig. 6 converge upwardly to a relatively narrow top wall which is disposed below the upper surface of the burner portion 40 and in which I provide a row of discharge orifices 48. The main burner portion 40 is provided with discharge orifices 49 along the sides of the cen-

tral opening. To bring the orifices 49 as close as possible to the orifices 48, the central opening in the main burner-portion is constricted at a point near the top of the burner-portion 41 and the sides of the central opening diverge upwardly above such constriction. The main-burner discharge orifices 49 are located in such upwardly diverging side walls to discharge obliquely upward above the burner-portion 41. Desirably, the orifices 49 along one side of the central opening in the main burner portion are staggered relatively to those along the opposite side to avoid impingement of the respective flames; and each of the orifices 49 in the burner portion 41 is disposed midway between two orifices 49 on opposite sides of the central opening.

Below the constricted portion of the central opening in the main burner-portion the side walls thereof diverge downwardly in spaced relation to the burner-portion 41 to provide passages 50 for the admission of secondary air.

In an arrangement such as that described, the mixture-supply conduits 44 and 46 may be brought outwardly through a side wall 53 of the oven where they are adapted to receive gas respectively from the conduits 26 and 27 illustrated in Fig. 1. As is clear from Fig. 4, the supply conduits 44 and 46 are enlarged beyond the side wall 53 of the oven to form chambers 54 each of which has an air-admission opening in its rear wall. The effective area of each of these openings may be regulated by a disk 55 supported on the rear end of a screw 56 which is screw-threadedly mounted in the front wall of the associated chamber 54 and which has associated with it a lock nut 57. Conveniently, the outer ends of the two conduits 44 and 46 are offset vertically so that both screws 56 are accessible from the front of the stove.

The passage 43 need not be continuous around the central opening. As is clear from the drawing, such passage is interrupted by a solid bridge-member 60 located centrally of the burner on the front side thereof. Conveniently, the upper surface of this bridge is located below the top of the burner-portion 41 so that it will be possible to observe, through a sight-opening (not shown) in the front wall of the oven, whether or not there are flames above the orifices 48 of the inner burner-portion 41.

The construction illustrated in Figs. 4 to 7 possesses all the advantages of that shown in Figs. 1 to 3. It has the further advantage, however, that only one half as many auxiliary orifices 48 are necessary to have one closely associated with each of the main orifices 49. I can thus increase the difference between the minimum and maximum capacities of the burner.

I claim as my invention:

1. In a gas range, a burner comprising a hollow member, a longitudinal partition within said hollow member dividing its interior into two independent mixture passages, said burner being provided exteriorly with a row of recesses substantially co-planar with said partition, each of said recesses communicating independently with said passages, a supply conduit for each of said passages and a temperature-responsive valve associated with one of said supply conduits.

2. In a gas range, a burner comprising a hollow member, a longitudinal partition within said hollow member dividing its interior into two independent mixture passages, said burner being provided exteriorly with a row of recesses substantially co-planar with said partition, each of

said recesses communicating independently with said passages, supply conduits of different cross-sectional areas for the respective gas passages, and a temperature-responsive valve associated with the supply conduit of larger cross-sectional area.

3. A gas burner having a series of burner ports and two independent mixture supply passages independently communicating with each of said ports through restricted openings, the openings through which one passage communicates with said ports being smaller than the openings through which the other passage communicates with said ports.

4. A gas burner having a series of burner ports and two independent mixture supply passages independently communicating with each of said ports through restricted openings.

5. A gas burner having a series of burner ports and two independent mixture supply passages independently communicating with each of said ports.

6. A gas burner having two independent mixture supply passages each having a series of discharge orifices, said orifices being arranged in pairs with the two orifices of each pair communicating respectively with said two passages, and a common port for each such pair of orifices.

7. A gas burner, comprising a U-shaped tube, a partition extending from one end of said tube to the other and dividing the interior of the tube into two independent mixture passages, a U-shaped row of burner ports co-planar with said partition and each communicating independently with said two passages, and two supply conduits communicating respectively with said two passages at points located on opposite sides of the intermediate leg of said U-shaped burner.

8. The invention set forth in claim 7 with the addition of means for independently controlling the supply of gas to each of said supply conduits, the control means associated with one conduit being temperature-responsive.

9. A gas burner provided with a supply passage having a row of upwardly directed discharge orifices, said burner also being provided with a second supply passage having two rows of discharge orifices located on opposite sides of said first passage and discharging generally toward each other over the orifices therein, and means for independently supplying gas to said two passages, said means including a temperature-responsive valve controlling the supply of gas to the second passage.

10. A gas burner provided with a supply passage having a row of upwardly directed discharge orifices, said burner also being provided with a second supply passage having two rows of discharge orifices located on opposite sides of said first passage and discharging generally toward each other over the orifices therein, and means for independently supplying gas to said two passages, said means including a temperature-responsive valve controlling the supply of gas to one of said passages.

11. A gas burner provided with a supply passage having a row of upwardly directed discharge

orifices, said burner also being provided with a second supply passage having two rows of discharge orifices located on opposite sides of said first passage and discharging generally toward each other over the orifices therein, and means for independently supplying gas to said two passages.

12. A gas burner, comprising a hollow elongated central portion, a hollow outer portion embracing said central portion but spaced therefrom, and conduits for supplying gas independently to the interiors of said hollow burner-portions, said central burner-portion being provided with a row of upwardly directed discharge orifices and said outer burner-portion being provided with two rows of discharge orifices located on opposite sides of and discharging generally toward each other over the row of orifices in said central burner-portion, the orifices of said outer portion being inclined upwardly toward said central portion to discharge obliquely thereover.

13. A gas burner, comprising a hollow elongated central portion, a hollow outer portion embracing said central portion but spaced therefrom, and conduits for supplying gas independently to the interiors of said hollow burner-portions, said central burner-portion being provided with a row of upwardly directed discharge orifices and said outer burner-portion being provided with two rows of discharge orifices located on opposite sides of and discharging generally toward each other over the row of orifices in said central burner-portion.

14. A gas burner having a main mixture supply passage and a smaller auxiliary mixture supply passage independent of each other, each of said passages being provided with a series of discharge orifices, the orifices in said auxiliary passage being directed generally toward the orifices of the main passage whereby any gas emerging from the orifices of the main passage will be ignited by the flames from the orifices of the auxiliary passage.

15. The invention set forth in claim 14 with the addition of means for independently controlling the supply of gas to each of said passages, the control means associated with said main passage being temperature-responsive.

16. The invention set forth in claim 14 with the addition that the orifices associated with said auxiliary passage are smaller than those associated with the main passage, and temperature-responsive means controlling the supply of gas to the main passage.

17. The invention set forth in claim 14 with the addition that the orifices associated with said auxiliary passage are smaller than those associated with the main passage.

18. The invention set forth in claim 14 with the addition that the orifices associated with said auxiliary passage are smaller than those associated with the main passage, and supply conduits for said two passages respectively, the supply conduit for the auxiliary passage being smaller in cross-sectional area than the other supply conduit.

JOHN E. CHAMBERS.
